CLAIM

The ornamental design for a kerosene stove, as shown and described.

DESCRIPTION

FIG. 1 is a perspective view of a kerosene stove showing my new design.

FIG. 2 is a rear side elevational view thereof.

FIG. 3 is a right side elevational view thereof.

FIG. 4 is a top plan view thereof.

The bottom surface of the stove is substantially planar and unornamented.

FIG. 1

FIG. 4
